INVENTOR:
HARRY PARK.

BY D. Fitzgerald ATT'Y.

UNITED STATES PATENT OFFICE.

HARRY PARK, OF PORTLAND, OREGON.

ADVERTISING AND DEMONSTRATING NOVELTY.

Application filed December 27, 1920. Serial No. 433,337.

To all whom it may concern:

Be it known that I, HARRY PARK, a citizen of the United States, residing in the city of Portland, county of Multnomah, and 5 State of Oregon, have invented certain new and useful Improvements in Advertising and Demonstrating Novelties, of which the following is a specification.

My invention relates more particularly to 10 new and novel advertising and demonstrating mechanism adapted to operate automatically and to actuate some article to be demonstrated and to manipulate cards or other advertising articles in connection 15 therewith.

My invention is preferably embodied in a figure representative of a human being, with actuating mechanism therein for operating the article to be demonstrated and for also 20 manipulating the cards or other articles, thus attracting attention to the exhibit which looks and acts as a human being performing the work.

The mechanism for manipulating or 25 changing the advertising cards may be similar to that shown in my United States Patent No. 1,279,142, issued to me September 17, 1918, for advertising novelty.

In order to fully describe my invention, I 30 have illustrated the same as a representation of a woman operating back and forth a carpet sweeper with one hand, and with the other hand changing the advertising cards on which are statements about the article 35 demonstrated.

In the drawings, Figure 1 is a front elevation of my invention as thus embodied;

Figure 2 is an enlarged view of the form, with parts broken away in order to show the 40 mechanical arrangement and connections;

Figure 3 is an interior view of the actuating mechanism; and

Figure 4 is a detail view of a form of valve for controlling the supply of matter 45 to be discharged in position to be picked up by the sweeper.

Referring more in detail to the drawings, Figs. 1 and 2, a main body frame, 1, 1, has mounted therein a motor, 2, which drives 50 a pulley, 3, by means of a belt, 4, said pulley being mounted on a shaft 5. Mounted on said shaft 5, is a pinion 6, which meshes with and drives a gear, 7, on a shaft 8, on which shaft is also a pinion 9, which meshes 55 with and drives a large gear, 10, provided

with a crank pin 11, to which is attached a crank 12, as clearly indicated in Fig. 3.

On the upper end of said body frame, in two bearing brackets, 13 and 14, are two shafts, 15 and 16, the shaft 15 being in two 60 sections, one section 15' being journaled at its inner end in the end of the other section, as at 15^a, clearly indicated in Fig. 3. On the shaft 16 is mounted a crank arm 17, while on the shaft section 15' is mounted a 65 crank arm 18, and on the shaft section 15 is mounted a crank arm 19. Mounted in the upper frame members, 20, 20, is a vertical shaft, 21, on which is a crank arm, 22, connected with the crank arm 19, by means of 70 a link 23. On said vertical shaft 21 is mounted a head, 24, to turn with said shaft.

A long link 25 connects the crank 12 with the crank arm 18, on the shaft section 15', while a tubular member 26, connects with 75 the crank pin 11, on the gear 10, and is connected at its upper end, by means of a telescoping rod and screw, 27, with crank arm 17, as clearly indicated in Figs. 2 and 3. On the screw rod 27, is a nut, 28, adapted to 80 be engaged by the upper end of the tubular member 26 on its upward movement.

Mounted on the tubular member is a pivoted latch member or dog, 29, the lower end of 85 which moves through an opening in the tubular member, as shown in Fig. 2, and engages a notch or shoulder, 30, on the inner rod, 27, whereby said tubular member 26 and said rod 27 are moved downwardly together until 90 said latch 29 engages a trip rod, 31, across the body frame 1, 1, which moves it out of the notch and allows said tubular member and latch to move downwardly over the rod 27, until the latch again engages with the rod, 27, in a second notch or shoulder, 32, 95 a short distance below.

Attention is called to the fact that the two notches 30 and 32 in the side of the inner rod 27, are not straight notches but that the upper side of each is tapered so that 100 the end of the latch 29 can only move the rod downwardly. When the latch 29 trips on the rod 31, the sleeve 26 and the latch move downwardly over the rod, the rod and arm 17 standing still for a moment, and 105 when the latch reaches the notch or shoulder 32, it operates to move the rod on down, moving the arm again, and as the gear 10 turns, the tube 26 moves upwardly until it engages the nut 28, and thus lifts the rod and arm 110

17 up. The arm 17 is stopped until the latch reaches notch 30 again, whereupon it is moved a short distance and stopped when the latch is again tripped on rod 31, as before.

This lost motion is for the purpose of intermittently stopping the movement of the sweeper. As the gear 10 turns, the connecting parts 25 and 26 turn with it, until the 10 latch 29 comes over and strikes the trip rod 31, whereupon the crank arm 17 stops while the tubular member 26 moves down and around with the crank pin 11, as indicated by the circular arrows in Fig. 2. As the 15 gear 10 continues to turn and the crank pin 11 comes up on the other side of the gear axis, the tubular member will rise on the rod 27 until it engages the nut 28, whereupon the crank arm 17 will be moved upwardly again and thus move the arm of the figure. The latch 29 will operate to engage with the notch 30 on the next downward move, as before.

Mounted on the outer end of the shaft 25 section 15', is an arm, 33, and on the outer end of the section 15 is an arm 34. The shaft 16 is provided with a gear 35, which meshes with a gear 37, on the shaft 15. Thus as the motor 2, through the connections described, 30 drives the gear 10, it operates, through the connections 25 and 26, to the crank arms 17 and 18, to oscillate the shafts 16 and 15' and the arm 33, and through the gears 35 and 37, between the shaft 16 and the shaft 35 section 15, to oscillate the arm 34, the connections being such that the arm 33, operating as a lever, moves back and forth, while the other arm 34, as a rigid lever, moves back and forth in an opposite manner. This 40 is due to the crank connections at 11 and 12, with the gear wheel 10. The arm 34 also has a shorter movement.

Connected with the right arm is a sweeper handle 40, of a sweeper, 41, which is being 45 demonstrated by the mechanism.

Mounted near the figure is a stand, 42, within which is a receptacle 43, containing sand, or other powdered matter to be discharged, a little at a time, on the floor in front of the sweeper. A discharge pipe, 44, is extended down to a position in front of the sweeper, as indicated, the outer end thereof being supported on a small standard 45. A valve mechanism is mounted at the bottom 50 of the receptacle, 43, to control the discharge of the matter therefrom. This valve mechanism is shown in Fig. 4, and comprises a double construction, a movable plate 46, with turned down ears, 46', 46', and a movable plate 47 with a handle 47'. Both are pivoted, as at 48, and are provided with openings, 46^a and 47^a. An opening 49^a in the base plate, 49, registers with the outlet from the container 43, as will be understood. 60 A spring 50, operates to normally hold the

plate members 46 and 47 drawn to the positions indicated in full lines, with the openings out of register. The handle 47' is connected by means of a link, 51, with a lever, 52, which is extended up to a position to be 70 engaged by the arm 34, as it moves back and forth, thus pulling the plates 46 and 47 in the direction indicated by the dotted line, until the openings register to permit the discharge. As the handle 52 moves under the tension of the spring 50, the plates 46 and 47 move to the positions indicated in full lines. The first movement of the plate 47 brings its opening 47^a into register with the opening 46^a in the plate 46, and from this point the plate 46 moves with the plate 47. The continued movement brings these two registering openings 46^a and 47^a into register with the opening 49^a, thus opening the discharge from the receptacle 85 80 43 to the pipe 44, which is positioned to discharge the small quantity of sand or flour on the floor in front of the sweeper. A hose 53 extends from the body of the sweeper, through the dust bag, and discharges back into the receptacle 43, as at 54, clearly indicated in Fig. 1. Thus the matter picked up from the floor by the sweeper is automatically discharged back into the receptacle 43 for reuse. 90 95

Mounted on the standard 42, is a display rack, 55, within which are display cards, 56, adapted to be interchanged with each other as the arm 34 of the figure is moved out and in, operated by the mechanism hereinbefore described. On the hand of the arm 34, is a projection 34^a, positioned to engage the vertical lever 52 for the purpose of intermittently operating said handle and the valve mechanism shown in Fig. 4 to make 100 105 the discharge of the matter to be picked up by the sweeper.

Thus I have provided a representation of a human figure, equipped with mechanism for automatically operating a sweeper or other device to be demonstrated, and also for automatically manipulating display matter about the article being demonstrated, thus making a most attractive and interesting, 110 demonstrating display, with a good representation of life, and while I have shown but one embodiment of my invention, I am aware that it can be embodied in other ways without departing from the spirit thereof, and I do not limit the invention hereto, except as I may be limited by the hereto appended claims. 115 120

I claim:

1. In a device of the character referred to, a two-part shaft having arms at its outer ends, a crank arm on each part of said shaft, motor means with operative connections to said crank arms for oscillating the same, and means interposed in said connections for intermittently moving said crank 125 130

arms during the continuous operation of said motor driven means, and the representation of a human figure enclosing said mechanism and the arms of which are the arms on the 5 outer ends of said shaft.

2. In a device of the character illustrated, in combination, the representation of a human figure having movable arm members, a motor driven mechanism in said figure, a 10 plurality of shafts, crank arms on said shafts for oscillating said shafts, the arms of said figure being connected, respectively, to the ends of said shafts, connecting rods from said motor driven mechanism to said 15 crank arms, said connections being adapted to cause a different movement of said arms relative to each other, a mechanism to be demonstrated by an oscillating movement thereof, said mechanism being connected to 20 one of said arms, display elements adapted to be moved by the other of said arms, and connections for moving said display elements, and means in the connections from the motor driven mechanism for causing an 25 intermittent movement of said arms during the continuous operation of said mechanism.

3. In a mechanism of the character represented, in combination, the representation of a human figure having arms and head 30 movable, motor driven mechanism within said figure, operating connections from said motor driven mechanism for intermittently moving said arms and said head during the continuous operation of said mechanism, a 35 mechanism to be demonstrated by an oscil-

lating movement thereof, said mechanism being connected to one of said arms to be moved intermittently thereby, display elements to be moved into and out of display position, means operated by the other of 40 said arms for shifting said display elements, and operating connections from an intermittently moved part for intermittently moving said head, substantially as described.

4. In a mechanism as illustrated, a representation of a human figure, shafts therein connected with the arms of said figure for moving the same, crank arms on said shafts, motor driven mechanism to be continuously driven, connections from said mechanism to 45 said crank arms said connections being adapted to intermittently operate said crank arms and said shafts during the continuous operation of said motor driven mechanism, a sweeper connected with one of said arms to be intermittently moved back and forth, display elements adapted to be shifted to and from display position by said other arm, with connections for engaging and moving the same, and means intermittently actuated 50 by said arm for discharging matter to be picked up by said sweeper, substantially as described.

Signed at Portland, Multnomah County, Oregon, this 14th day of December, 1920.

HARRY PARK.
